UNITED STATES PATENT OFFICE.

ALEXANDER J. BERGERON, OF DES MOINES, IOWA.

BAG AND HOLDING AND RELEASING DEVICE.

1,206,747.

Specification of Letters Patent. Patented Nov. 28, 1916.

Application filed January 31, 1916. Serial No. 75,473.

To all whom it may concern:

Be it known that I, ALEXANDER J. BERGERON, a citizen of the United States, and resident of Des Moines, in the county of Polk and State of Iowa, have invented a certain new and useful Bag and Holding and Releasing Device, of which the following is a specification.

The object of my invention is to provide a collapsible bag waterproof and air-tight adapted to be sunk in the water and to be inflated for raising loads.

A further object is to provide such a bag having outside rigid reinforcing members capable of lying in two flat superposed rows or of moving to position for forming a cylinder, and adapted to reinforce and support the bag.

Still a further object is to provide such a bag having a trip member at its lower end, in combination with an anchoring device adapted to engage said trip member.

Still a further object is to provide an anchoring device, and a device adapted to be grasped and held thereby, said second device being adapted to hold a rope and to release the rope when received within the anchoring device and moved in one direction with relation thereto.

My invention consists in the construction, arrangement and combination of the various parts of the device, whereby the objects contemplated are attained as hereinafter more fully set forth, pointed out in my claims, and illustrated in the accompanying drawings, in which:

Figure 1 shows a side elevation, partly in section of a bag embodying my invention. Fig. 2 shows an enlarged, detail view of the upper end thereof, partly in section. Fig. 3, shows a horizontal, sectional view of part of the bag wall. Fig. 4 shows a vertical, sectional view of part of the bag wall. Fig. 5 shows a top or plan view of the upper flat member of the bag showing the manner in which the reinforcing ropes or cables are secured thereto. Fig. 6 shows a vertical, sectional view of the anchoring device, and the catch member received therein. Fig. 7 shows a horizontal, sectional view taken on the line 7-7 of Fig. 6, and Fig. 8 shows a top or plan view of the anchoring device, the shank of the catch member being shown in horizontal section.

In the form of my invention, illustrated in the accompanying drawings, I have used the

reference numeral 10 to indicate generally a waterproof air-tight bag of suitable material having a central opening 11 at its upper end. An annular ring 12 is placed adjacent to the inner surface of the bag 10 around the opening 11. On the outside of the bag on the upper end thereof is a disk 13, having at its periphery an outwardly extending flange 14. The disk 13 is provided at its central portion with an upwardly extending cylinder 15, on the interior of which is an annular shoulder 16 forming a valve seat having a downwardly opening hinged valve 17.

Communicating with the upper end of the cylinder 15 is a tube 18. At the lower end of the bag is an annular ring 19 to which is secured a downwardly extending shank 20. Surrounding the central portion of the bag is a plurality of upright rigid members 21 which may be made of wood or the like. Reinforcing cables or ropes 22 are secured to the ring 19 and extend upwardly from the rigid reinforcing member 21 through grooves 23 in the upper ends of the members 21. There are preferably two of the ropes or cables 22 for each reinforcing member 21. At its upper end each rope or cable 22 is extended through an opening in the flange 14 of the disk 13, thence downwardly through another opening, as clearly illustrated in Fig. 5.

Secured to the upper ends of the members 21 and covering the upper end of the bag 10 is a screen or meshed covering 24. The ring 12, the disk 13 and the upper edges of the meshed screen 24 and bag 13, and the upper edges of the meshed screen 24 and bag 10 are all secured together by means of suitable bolts or the like 25, on which are nuts 26.

Secured to the lower ends of the members 21 is a similar meshed screen 27 covering the lower end of the bag. It will be noted that the lower end of the bag extends to the point A, and not to the lower ends of the members 22.

At the lower end of the shank 20 is a hollow cylinder member 28, having a solid partition or cover member 29 in its upper end screwed on to the lower end of the shank 20. At the lower end of the cylinder 28 is a cone-shaped downward extension 30 having a central opening 31 into which the lower end of the shank 20 is secured. The lower end of the shank 30 has a vertical

elongated opening 32, to receive a head 33 on the end of the cable or rope 34.

In the wall of the lower portion of the shank 20, which has the opening 32, are slots 35 in which are pivoted bell crank levers 36. Springs 37 may be supported on the portion 30 to normally engage the outwardly extending arms of the bell crank levers 36 for holding the other arm thereof inwardly in the interior of the lower hollow portion of the shank 20.

Pivoted to the outer ends of the bell crank levers 36 are upwardly extending rods 38 slidably extended through the cover member 29 and normally projecting above said cover member.

On the lower end of the shank 20, which has just been described, I provide an anchor device comprising a hollow cylinder 39 having on its lower end a hook member 40, with a catch 41 pivoted thereto. The lower end of the anchor member may be of any desired form.

At the upper end of the cylinder 39 are opposite pairs of upwardly extending members 42, shown in Figs. 6 and 8. Mounted within the members 42 is an annular ring 43. Hinged to the lower edge of the ring 43 on opposite sides thereof are flat members 44 adapted to swing downwardly within the cylinder 39. The members 44 are normally held upwardly in position engaging the lower edge of the ring 43 by means of springs 45, secured to said members 44 and to the ring 43, above said members.

My improved bag holding device is designed for use in raising sunken wrecks and the like from the bottom of the sea.

40 The members 21 are flexibly hinged together also by means of flexible cables or ropes 48 extending through them circumferentially of the bag.

In the practical use of my improved invention, the anchor device is taken to the bottom of the sea and anchored to the wreck or the load to be raised by divers or by means of another invention of mine not herein further referred to.

50 In the lower portion of the anchoring device is rotatably mounted a pulley 46. When the anchoring device is secured to the load to be raised, the cable 34 is left on the pulley 46. One end of the cable is placed in the hollow lower end of the shank 20 of one of my bags. The anchoring device having been fixed, the cable 34 is manipulated for drawing the bag downwardly. The bag is, of course, drawn through water in its collapsed form, the sides being laid close together and the bag being flat. When the bag is drawn downwardly to the position where it reaches the anchoring device, the members 30 and 28 are drawn into the cylinder 39 forcing the members 44 down-

wardly until the cylinder 28 releases said members 44. When the parts are in this position, the pull on the cable is released, the tendency of the bag to float upwardly in the water will draw the partition 29 against the members 44, thereby causing the rod 38 to engage the members 44 and release the bell crank levers from the member 33, whereupon the cable 34 will be released.

The bag may be filled by means of compressed air fed to it through the tube 18. As many air bags may be attached to the load to be raised as is necessary for the purpose.

When the bags reach the surface, the load 80 can be handled by the ordinary methods employed by salvage crews and the bags released and laid on the deck of the boat or the like, until there is no air in them.

It will be noted that when the bag is in 85 the water, considerable pressure will be necessary to fill it, in order to overcome the water pressure. When the bag is out of the water, the tube 18 can be released from the cylinder 15 and the valve 17 opened, emptying the bag of air.

Some changes may be made in the construction and arrangement of the parts of my improved bag without departing from its essential features and purposes, and it is 95 my intention to cover by this application any such changes which may be included within the scope of my claims.

I claim as my invention:

1. A device of the class described, comprising an air-tight water proof bag, having an opening, a valve for closing said opening, air supply tubes communicating with said opening adjacent to said valve, a plurality of rigid reinforcing members arranged circumferentially of the central portion of said bag flexibly hinged together at their side edges means for supporting said reinforcing members against longitudinal movement with relation to the bag, a rigid member mounted at the upper end of the bag, a rigid member mounted below the lower end of the bag, and a supporting and reinforcing member capable of connecting said rigid members and extending from said first described reinforcing members.

2. In a device of the class described, an air-tight water proof bag having an opening at one end, a rigid reinforcing member on the interior of said bag, surrounding said opening, a rigid reinforcing member on the exterior of said bag surrounding said opening, a valve seat formed on the interior of said second member, a valve adapted to contact with said seat, said second rigid member having a central opening adjacent to said valve seat, rigid reinforcing members arranged in a series around the circumference of the central portion of the bag, said members being flexibly connected together, a

- meshed reinforcing member secured to the upper ends of said last described reinforcing members and to the second rigid member at the upper end of the bag, a rigid 5 member below the lower end of the bag, a meshed reinforcing member covering the lower end of said bag and secured to the lower ends of said flexibly connected members, reinforcing members capable of securing 10 the rigid member at the top of the bag and the rigid member at the lower end thereof, and extending outside said flexibly connected reinforcing members.
3. In a device of the class described, an 15 anchor comprising a cylinder, a grappling device at one end thereof, a rotary member mounted in said cylinder below the upper end thereof, downwardly opening hinged members at the upper end of said cylinder, 20 means for limiting the upward movement of said hinged members, means for yieldingly holding said hinged members in their upper position, and a coacting device comprising a shank having an enlarged head 25 thereon.
4. In a device of the class described, an anchor comprising a cylinder, a grappling device at one end thereof, a rotary member mounted in said cylinder below the upper 30 end thereof, downwardly opening hinged members at the upper end of said cylinder, means for limiting the upward movement of said hinged members, means for yieldingly holding said hinged members in their upper 35 position, and a coacting device comprising a shank having an enlarged head thereon, said coacting device having in its lower end an opening receiving a rope, pivoted trigger members projecting into said opening, upper 40 right rods pivotally mounted on said trigger members and projecting upwardly above the head of said shank.
5. In a device of the class described, an anchor comprising a cylinder, a grappling device at one end thereof, a rotary member mounted in said cylinder below the upper 45 end thereof, downwardly opening hinged members at the upper end of said cylinder,
- means for limiting the upward movement of said hinged members, means for yieldingly holding said hinged members in their upper position, and a coacting device comprising a shank having an enlarged head thereon, said coacting device having in its lower end an opening receiving a rope, 50 trigger members projecting into said opening and pivotally mounted on the coacting device, upright rods pivotally connected with said trigger members and projecting upwardly above the head of said shank, a 55 rope member extended around the said rotary member having a head thereon adapted to be received in the lower end of said coacting device.
6. In a device of the class described, the 60 combination of an inflatable bag with an anchoring device, said bag and anchoring device having engaging members adapted to coact for locking them together when they are moved to certain relative positions, 65 a rotating member on said anchoring device, a flexible member extended through a portion of said anchoring device and extended over said rotary device and means for securing said flexible device to the engaging device on the bag adapted to automatically release the flexible device when said engaging device is in a certain relative 70 position and the bag is drawn away from the anchoring device.
7. In a device of the class described, the 75 combination of an engaging member with an anchoring device adapted to receive said engaging device, means on said anchoring device for holding said engaging device 80 against the removal of the said anchoring device when the engaging device is so received, a flexible device extended through a portion of the anchoring device and means for securing one end of said flexible 85 device to said engaging member adapted to automatically release said flexible device when force is applied to draw said engaging member out of said anchoring device.

Des Moines, Iowa, January 12, 1916.
ALEXANDER J. BERGERON.
